UNITED STATES PATENT OFFICE.

RUFUS S. MATTESON, OF PROVIDENCE, RHODE ISLAND, ASSIGNOR TO THE PHENIX IRON FOUNDRY, OF SAME PLACE.

CLOTH-TENTERING MACHINE.

SPECIFICATION forming part of Letters Patent No. 350,009, dated September 28, 1886.

Application filed June 11, 1886. Serial No. 204,896. (No model.)

To all whom it may concern:

Be it known that I, RUFUS S. MATTESON, of the city and county of Providence, and State of Rhode Island, have invented a new and useful Improvement in Cloth-Tentering Machines; and I do hereby declare the following specification, taken in connection with the accompanying drawings, forming a part of the same, to be a description thereof.

10 This invention relates to those well-known machines for tentering cloth in which traveling chains provided with clamps or tenter hooks or pins are caused to move along two side rails and carry the cloth through the 15 drying-room. In one class of these machines these rails have longitudinal reciprocating movements imparted to them for the purpose of producing a desirable finish on the cloth, and most of these machines are arranged so 20 that said rails can be laterally adjusted with relation to each other to receive fabrics of different widths. The machines are furnished at the delivery end with a roller which receives the 25 fabric from the traveling or conveyer chains, and acts as a guide in delivering the fabric from the machine. In machines whose rails are given longitudinal reciprocating movements this delivery-roll has been pivoted to the rails at points near the outer edges thereof—that is, at points outlying the edges of the 30 fabric—and as the roll swings with the rails the cloth in passing over the roll has been alternately slackened and tightened on the roll from the central line of the fabric toward its 35 edges, thereby drawing it out of shape and straining it. In machines having the rails laterally adjustable with relation to each other the delivery-roll has been made telescopic in form, in order that its length might 40 be increased and diminished as the rails were moved farther apart or brought nearer together to accommodate fabrics of different widths. In a roll of telescopic form one or more of its sections must be the larger, which 45 produces one or more circumferential ridges on the roll. These ridges crease the finished fabric, and thereby give it an undesirable appearance.

The objects of the invention are to prevent 50 the fabric passing through the machine from being slackened and tightened on the delivery-

roll, as described, and to prevent the creasing of the finished fabric by ridges on said roll, and yet the roll be able to deliver any width of fabric within the limits of the machine.

55

To these ends the invention consists in pivoting the delivery-roll to or with relation to the side rails of the machine at points substantially in vertical planes passing through the gripping-faces of the clamps or the tenter-pins, 60 whereby a slackening and tightening of the fabric on said roll is avoided, and in making the said roll without peripheral ridges and mounting it so as to allow of a lateral adjustment of the rails, as will hereinafter appear. 65

In the accompanying drawings, Figure 1 represents a top view of the delivery end of a tentering-machine embodying the invention, (portions of the same being broken away,) the rails of which have longitudinal reciprocating 70 movements and are adjustable laterally with relation to each other. Fig. 2 shows a side view of the same, a portion of the mechanism shown in Fig. 1 for reciprocating the rails being omitted. Fig. 3 represents an end view of a 75 portion of the delivery end of the machine, showing the manner in which the delivery-roll is mounted, the mechanism shown in Fig. 1 for reciprocating the rails being omitted. Fig. 4 represents a similar view of a machine, 80 showing how the ordinary delivery-roll is mounted. Fig. 5 represents a top view of a portion of the side rails of the machine, and is a diagram illustrating the difference between pivoting the delivery-roll in accordance with 85 my invention and in the ordinary way.

A A' are the side rails of the machine, which are mounted in a well-known manner and support the traveling or conveyer chains B B'.

90

C is one of the screws for laterally adjusting the rails with relation to each other, the said screw having central bearings in lugs c on the arm C', (which arm is pivoted upon a stand-ard, C',) and being threaded through blocks 95 a a', to which the rails are pivoted. The chains B B' are provided with well-known clamps b b' or well-known tenter-pins, b", Fig. 3, for holding the fabric at its edges, and said chains pass over sprocket-wheels at each end of the machine, those, D D', at the delivery end of the machine being attached to gears E E', re-

100

spectively. Meshing with these gears are two pinions, one of which, f , is shown in Figs. 1 and 2, and these pinions are mounted upon a shaft, F, centrally pivoted on a standard, G, so as to swing. The shaft F is furnished with a bevel-gear, f' , through which revolution is imparted to the shaft from the usual source of power. The shaft F also passes through blocks g g' , which are pivoted to the rails. A swinging motion is given to the shaft F, and thereby a reciprocating motion to the rails, by a crank-disk, H, Fig. 1, which is revolved in a well-understood way, and is connected by a rod, h, to one end of the shaft F. The shaft F at its ends is furnished with rollers f'' , which rest and roll upon standards J J'.

As thus far described, the machine is well known and understood by builders and users of tentering machinery.

K, Figs. 1, 2, and 3, is my improved delivery-roll, which has an unbroken surface, and is mounted to revolve in arms k, secured to a rod, L, the said arms and rod forming a yoke or frame in which the roll is mounted to revolve. To the rod L is preferably centrally secured a stud, l, which enters a bracket or support, M, and pivots the rod thereto. Upon the rod L sleeves N N' are mounted to slide, said sleeves being provided with depending studs n n', which enter arms O O', respectively attached to the rails A A', and pivot said sleeves, and consequently the rod L and roll K, to said arms. The centers of the pivotal connections between the sleeves N N' and arms O O' are located substantially in vertical planes passing through the gripping faces or lines of the clamps b b', or the tenter-pins b'', as shown in Fig. 3. I say "substantially" because I prefer to arrange these pivotal centers as nearly as possible vertically above the edges of the fabric, P, held by the clamps or pins, and shown by dotted lines; but as the edges of the fabric are but a fraction of an inch from the gripping faces or lines of the clamps or the tenter-pins, even then the centers of pivotal connection would be substantially in vertical planes passing through said clamp-faces or the pins. It will be readily seen, therefore, that those portions of the roll K with which the edges of the cloth come in contact will have the same amount of reciprocating movement as the edges of the fabric; consequently the fabric will not be slackened and tightened on the roll during its delivery, as it would be upon a roll pivoted to the rails near the outer edges of the latter, as will soon be illustrated.

Referring to Fig. 4, K' shows an ordinary telescopic roll, which is composed of three sections, k' k'' k'', the end sections being greater in diameter than the middle section. This roll is mounted to revolve in studs p p', which are pivoted in standards p'' p''' near the outer edges of the rails, according to the prevailing custom. The centers of the pivotal connection between the studs p p' and standards p'' p''' (and consequently between the roll K' and the rails A A') considerably outlie the edges of the fab-

ric P, (shown in dotted lines,) and as the studs p p' have the same amount of reciprocating movement as the rails and the cloth which the chains B B' carry, those portions of the roll K' with which the edges of the cloth come in contact during delivery will have less motion than the edges of the fabric. This will be clearly seen by an examination of Fig. 5, in which the centers of pivotal connection between the studs p p' and standards p'' p''' are represented by the centers of the dotted circles r r' and r'' r'', the dotted lines x x representing the longitudinal axis of the roll K' when in its two extreme positions of movement. When the rail A' has been fully advanced, the left-hand edge of the fabric P will have been moved forward to the point s; but the roll will only have advanced to the point s', in line with the edge of the fabric; consequently the fabric will be slack on the roll from the center t of the former to its left-hand edge. On the other hand, the retreat of the rail A will carry the right-hand edge of the fabric back to the point u; but that portion of the roll in line with the fabric's edge will only have retreated to u'. Therefore the cloth will be stretched over the roll, increasing in tightness from the center t to the right-hand edge. Likewise, when the rail A is fully advanced, the right-hand edge of the fabric will be moved to the point v; but the roll in line with the edge of the fabric will only have moved to v', causing a slackness of the cloth in that side; and by the retreat of the rail A' the left-hand edge of the cloth will move to w, but the roll in line with the edge of the fabric will only have moved to w', causing a tightness or strain of the fabric on that side. This slackness and tightness of the cloth on the roll distorts the fabric and injures it, and the sections k' k'' being greater in diameter than the section k'' the ridges k' at the junction of the sections crease the cloth and damage its appearance.

Referring to Figs. 3 and 5, it will be seen that as the centers of pivotal connection between the roll K and the rails A A' are located substantially in vertical planes passing through the edges of the fabric those portions of the roll with which said edges should come in contact will be advanced and retracted by the movements of the rails equally in amount with the edges of the fabric. (The dotted lines y y, Fig. 5, indicate the axis of the roll K in different positions.) Therefore the cloth will not be slackened or tightened on the roll during delivery, and be thereby distorted.

In order that the roll K may be adapted for use with any width of fabric which can be centered on the machine, the roll is made long enough to take the widest fabric. When the rails A A' are adjusted laterally, the sleeves N N' (being pivoted to the arms O O', which are secured to the rails) will slide on the rod L, and in their new positions on said rod will impart a proper motion to the frame k L and the delivery-roll mounted therein.

Although I prefer to pivot the roll K cen-

trally by means of the stud *l* and bracket *M*, yet such central pivoting may be dispensed with, and one of the sleeves, as *N'*, may be secured to the rod *L* by a set-screw. (Shown by 5 dotted lines in Fig. 3.)

What I claim as my invention, and desire to secure by Letters Patent, is—

1. The combination, substantially as hereinbefore set forth, with the rails and traveling 10 chains provided with clamps or tenter-pins, and means, substantially as described, for reciprocating said rails, of a delivery-roll pivoted with relation to said rails substantially in vertical planes passing through the gripping- 15 faces of the chain-clamps or tenter-pins, as described, whereby a slackening and tightening of the fabric on the delivery-roll while passing over the same is avoided.

2. The combination, substantially as herein-

before set forth, with the rails and means, substantially as described, for laterally adjusting the rails with relation to each other, of a delivery-roll, a yoke or frame in which said roll is mounted, and connections, substantially as described, between said frame and the rails, 20 whereby one or both of the rails may be slid laterally with relation to the roll.

3. The combination, with the rails *A A'*, of the roll *K*, a yoke or frame, *k l*, in which said roll is mounted, a support, *M*, to which the 25 yoke is pivoted, the arms *O O'*, secured to the rails, and the sleeves *N N'*, mounted on the yoke and pivoted to said arms, substantially as and for the purposes specified.

RUFUS S. MATTESON.
